FRANK H. BENTON, OF TOPEKA, KANSAS

LOCOMOTIVE VALVE GEAR

Application filed February 10, 1927. Serial No. 167,092.

My invention more specifically stated relates to an improvement adapted to the Walschaert valve gear employed on locomotives whereby the starting power of a locomotive will be increased.

My invention has for its object the provision of means which may be readily applied to the Walschaert type of valve gear, whereby the travel of the steam control valve can be increased to any desired amount without, however, producing unsatisfactory and undesirable angles or cramped conditions in the valve gear parts.

The Walschaert valve gear as at present constructed and employed is limited in the amount of valve travel produced thereby, without introducing undesirable and unsatisfactory angles in the working parts of such valve gear. Furthermore, it is very often difficult to obtain equal leads with the present type of Walschaert valve gear because of certain conditions encountered on the locomotive.

On the other hand, long valve travel is quite desirable because it not only increases the starting power of a locomotive, but also permits of a reduction in steam consumption.

With my invention, means are provided for correcting the leads so that perfectly equal leads can be obtained at all points of the cut-off.

The above enumerated objects and advantages of my invention, as well as other advantages inherent in the construction, will all be more readily comprehended from the detailed description of the accompanying drawing, wherein:—

Figure 1 is an elevation of a portion of a locomotive and Walschaert valve gear provided with my improved means.

Figure 2 is a cross-section taken substantially on the line 2—2 of Figure 1, looking in the direction of the arrows.

Figure 3 is a detail view in perspective of my improved lever element.

Figure 4 is a detail view in perspective of my improved valve rod.

In the particular exemplification, merely portions of a locomotive, steam chest, cylinder and the running gear are shown; one end

of the steam chest being shown at 10, and one end of its valve at 11. The adjacent end of the cylinder is shown at 12, with the steam introducing port 13 leading from the steam chest; while the piston-rod is shown at 14. The piston-rod 14 connects with the cross-head 15, which carries the usual wrist-pin 16 to which one end of the connecting or main rod 17 is secured.

A portion of the usual reach-rod, which connects with the lever in the locomotive-cab, is shown at 18; with the usual link 19 and radius bar or rod 20, the lower end of the link 19 being provided with the usual eccentric rod 21.

As the various elements thus far referred to are features of the well known type of Walschaert valve gear, a more detailed description thereof need not be entered into.

The steam chest or valve chamber head 22 is shown provided with a rearwardly extending bracket 23 which is preferably formed integral therewith. Mounted on the opposite or inner side of the head 22, but not shown in the drawing, is the usual valve-steam cross-head to which the usual lap and lead or combination lever 24 is connected by a pin indicated in dotted lines at 25. The lower end of the combination lever 24 is pivotally connected at 26 to the usual lap and lead connector or union link 27.

My invention involves the introduction of a suitable lever 28 which is shown in detail in Figure 3. This lever 28 consists of a suitable casting or member of comparative thickness, provided adjacent to the upper end with an opening or pin receiving hole 29; at an intermediate point with a pin-receiving hole 30 which is preferably surrounded, on both sides of the lever, with bosses as at 31, 31. The lever is preferably shown, somewhat enlarged toward the lower end which terminates in the laterally disposed bosses or trunnions 32, 32; the lever and trunnions being apertured to provide a pin-receiving hole 33 for pin 34 whereby the lever 28 is pivotally connected to the bracket 23; the pin 34 constituting the fulcrum point of lever 28.

As shown, the centers of openings 29 and 33 are in alignment, while the center of open-

ing 30 is slightly off-set from a vertical line through the centers of openings 29 and 33.

I show lever 28 at top preferably provided with a lubricant-holding pocket or socket 34 which has ports leading from the bottom for conveying lubricant to the pins which are located in holes 29 and 30; while the enlarged lower end on one side thereof is shown provided with a lubricant-holding hole 35 having a duct leading to the fulcrum pin mounted in hole 33.

The intermediate hole 30 receives pin 36 whereby radius rod 20 is pivotally connected with lever 28.

15 The lever 28 is connected to the combination lever 24 by means of the rod or link 37 which is shown in detail, Figure 4. The link 37 is preferably shown provided with bifurcated ends 38, 39; the bifurcations 38 being intended to straddle the upper end of lever 28 and is pivotally secured thereto by pin 40 which passes through hole 29 in lever 28; while the bifurcations 39—shown spaced slightly farther apart—are intended to straddle the upper end of the combination lever 24, being pivotally secured thereto by pin 41; the bifurcations at both ends of the link 37 being provided with aligned pin-receiving holes 42 as shown in Figure 4.

30 It is apparent, however, that the lever 28 and link 37 may be of any suitable construction.

In operation, it will be seen that reciprocatory movement of radius rod 20 will impart movement to lever 28 about its fulcrum point 34, thereby moving link 37. The combination lever is actuated by the valve rod 37 and the union link 27 conjointly; and as the combination lever 24 is also connected through the medium of pin 25 and the usual cross-head (not shown) with valve-stem 43 of the steam valve 11, it is evident the valve 11 is therefore also moved accordingly.

As radius rod 20 is connected to lever 28 at a point intermediate of the fulcrum point 34 of lever 28 and the point of connection 40 with link 37, it is apparent that the point 41 is given greater movement than point 36 and as a result the travel of the valve 11 in the steam chest is also increased through movement of link 37 connected with the combination lever 24 whereby the valve 11 is controlled.

With my invention, all inequality of the leads can be easily corrected by modifying the slope of the link member 37, namely by raising or lowering its points of pivotal connection; such modification being dependent upon the length of lever 28 and the location of its fulcrum point relative to the lower end of the lever.

In applying my invention to the well known types of Walschaert valve gears, the only modifications that need be made in 65 such gear mechanism is to correspondingly

shorten the length of the radius rod 20 and likewise change the radius of the link element 19; that is to say, the radius of link element 19 should be reduced an amount equal to the reduction in length of the radius rod 20. 70

As previously described and as shown in the exemplification, the hole 30 for pin 36 is shown somewhat rearward, relatively to the steam-chest, of a vertical line between pins 34 and 40; this being done to obtain uniform motion of lever 28 for the valve gear mechanism as illustrated in the drawing. It will be understood, however, that in certain constructions of gear mechanisms, it would be practicable to place the opening 30 for pin 36 in a direct vertical line with the openings 29 and 33 and again in other instances to place the opening 30 somewhat forward of the vertical line between openings 29 and 33. 85

From the foregoing description and the disclosure made in the drawing, it is apparent that my invention, somewhat specifically stated, consists in introducing a starting power lever mechanism with certain pin connections and providing a suitable fulcrum or stationary pin-receiving member shown in the nature of a bracket 23 secured on the steam chest head 22; and while the invention has been shown applied to a well known type of 95 Walschaert valve gear mechanism in present use and has been described in terms used merely as terms of description and not as terms of limitation, modifications may be made without, however, departing from the 100 spirit of my invention.

What I claim is:

1. In combination with a valved chamber head, a valve stem cross-head, a locomotive valve gear involving a combination lever and a radius rod, a rearwardly disposed bracket secured to the valve chamber head, a vertically disposed lever fulcrumed at its lower end on said bracket, a horizontally disposed link pivotally connected at one end to the upper end of said lever while the other end of the link is pivotally connected to the upper end of the combination lever of the valve gear above its connection to the valve stem cross head, while the radius rod of the valve gear is pivotally connected to said first lever at a point below the pivotal connection of said first lever with said horizontally disposed link. 110

2. In combination with a valved chamber head, a valve stem cross-head, a locomotive valve gear involving a radius bar and a combination lever, a rearwardly disposed bracket secured to the valve chamber head, a vertically disposed lever provided with three pin receiving openings therethrough, one of said openings being at the upper end, a second at the lower end, while the third is at an intermediate point adjacent to the first mentioned opening, said lever having oil chambers in 125

its top and sides communicating with said pin-receiving openings, the lower end of said lever being fulcrumed on said bracket, while the intermediate pin receiving opening provides pivotal connection with the radius bar of the valve gear, and a horizontally disposed link having bifurcated ends with one end pivotally connected at the upper pin receiving opening of said lever while the other end of said link is pivotally connected to the upper end of the combination lever of the valve gear above the pivotal connection of said combination lever to the valve stem cross head of the locomotive.
